CLAMSHELL BUCKET

William Mayo Venable, Pittsburgh, Pa., assignor
to Blaw-Knox Company, Blawnox, Pa., a corporation of New Jersey

Application August 18, 1939, Serial No. 290,807

3 Claims. (Cl. 37—188)

This invention relates to clamshell hoisting buckets and, particularly, to buckets of large capacity, i. e., several tons.

Various types of clamshell buckets have been known heretofore, among them a bucket of such construction that the cooperating scoops thereof are actuated in such manner that their initial closing movement causes tilting of the scoops so that on further closing, the scoops execute a shoveling action as contrasted to the scraping action effected by scoops of the construction usually employed in buckets of small capacity. Brown Patent 302,133 discloses one form of bucket so constructed that its scoops perform a digging rather than a scraping movement. The construction disclosed in this patent, however, in common with all other buckets of similar construction with which I am familiar, has a serious disadvantage in that the guide mechanism employed to center the scoop hinges extends below the lower extremity of the movement of such hinges and is thereby subjected to impact as the bucket is dropped on a pile of material to be hoisted. This condition has been the source of much trouble and expense in the maintenance of large capacity buckets.

I have invented a novel construction of clamshell bucket which overcomes the aforementioned objection to bucket constructions previously known and provides a structure which is much simpler and less expensive than those employed heretofore. In the preferred embodiment of the invention, I provide a supporting frame or shroud to which a pair of cooperating scoops are pivotally connected by links. The scoops have arms or hinge plates pivoted to a closing sheave block. Inside the shroud are centering guides for the closing sheave block. The guides terminate short of the lowermost position of the block and are thus protected from contact with the material being handled at all times.

The pivotal axes of the scoops and their supporting links are so disposed that on the initial closing movement, the scoops move rapidly from a substantially vertical position to a position inclined at a substantial angle to the vertical, whereby the scoops on the remainder of their closing movement execute a digging operation rather than a mere scraping.

When the scoops are in their extreme wide-spread position, the closing sheave block is below the lower ends of the centering guides but I provide stops within the shroud adapted to cooperate with portions of said links projecting upwardly and inwardly of the shroud, to maintain

the scoops in approximately central position, although permitting departures therefrom in either direction to a limited extent.

Further details of the construction and the advantages thereof will become apparent during the course of the following description which refers to the accompanying drawings illustrating a present preferred embodiment. In the drawings,

Fig. 1 is a side elevation, partly broken away and partly in section;

Fig. 2 is a side elevation showing successive positions of the scoops and related parts during the closing operation; and

Fig. 3 is an end elevation, partly broken away and partly in section.

Referring now in detail to the drawings, the bucket of my invention comprises generally a supporting superstructure in the form of a shroud or frame 10 and cooperating scoops 11 and 12 secured thereto by links 13 and 14. The frame 20 or shroud 10 is preferably a fabricated plate structure including side plates 15 and end plates 16 riveted or otherwise suitably secured together. Stiffening channels 17 extend along the lower edges of the side plates 15 and cross braces 18 25 are secured to the inner surfaces of the end walls 16 to give the shroud rigidity transversely.

A head casting 19 is mounted on top of the shroud and is provided with anchorages 20 for holding lines 21 and rollers 22 for guiding the 30 ends of closing lines 23 which are taken in to effect a closing operation of the bucket. The other ends of the closing lines indicated at 23a are secured to dead ends on the crane by which the bucket is lifted.

A head block 24 is secured in the upper portion of the frame 10 and is provided with sheaves 25. The structure of the head block is not illustrated in great detail since the present invention does not concern it particularly and various designs of head blocks are already known.

The closing lines 23 are effecting to raise or lower a closing sheave block 26 in which sheaves 27 are journaled. The reeving of the closing cables may be traced by starting at the ends 23. 45 Commencing at the head casting 19, the lines 23 extend downwardly around one of the two middle sheaves 27, thence upwardly around one of the two middle sheaves 25 which are disposed at an angle so as to guide the cable downwardly in alignment with the second sheave from the outside of the lower block. After passing around this sheave, the cable then passes around the outside sheave 25 and thence around the outside sheave 50 55

27, and thence, as the fixed closing line 23a, to a dead end on the crane.

The scoops 11 and 12 have arms or hinge plates 28 extending inwardly and upwardly from each side thereof. Castings 29 secured to the plates 28 provide trunnions cooperating with hinge pins 30 secured to the sheave block 26. The scoops are thus hinged to the lower sheave block. The trunnions 29 have meshing gear segments 10 31 formed integral therewith insuring related angular movements of the two scoops. This is a known expedient for maintaining the block 26 in proper relation to the plane defined by the cutting edges of the scoops 11. The trunnions 15 also have pads 32 thereon adapted to cooperate with stops 33 on the sheave block 26 to limit angular movement of the scoops. The extreme widespread position of the scoops is shown in Fig. 2 in chain lines.

20 Guide rollers 34 are journaled on shafts 35 projecting from opposite ends of the sheave block 26. Centering guides 36 extend downwardly inside the frame or shroud 10 along opposite side plates. These guides are in the form 25 of channels with their lower ends flaring downwardly as at 37. They are formed by plates 38 welded edgewise in spaced relation to the side plates 15. It will be noted that these plates terminate at the lower flange of the channels 17. 30 The centering guides 36 cooperate with the rollers 34 to centralize the sheave block 26 relative to the frame 10 as it is drawn upwardly therein to effect a closing operation of the scoops. Bent bars 39 are welded to the sheave 35 block 26 in overhanging relation to the rollers 34 to act as a guard for the latter to preserve them from shock or impact when the bucket is opened.

The links 13 and 14 may be castings but in the embodiment shown are fabricated from pieces 40 of plate, one link being pivoted to each corner of the shroud or frame as at 40 and to one of the rear upper corners of the adjacent scoop as at 41. The links pivoted to each scoop are connected by angle bars 42 and a web plate 43. 45 This framework connecting the links pivoted to the same scoop gives the whole structure great stiffness laterally.

The links 13 and 14 have portions 44 extending inwardly and upwardly relative to the shroud. 50 Cross channels 45 extend between the stiffening channels 17. Stop plates 46 are welded between the channels 45 and 17 in the path of the ends of the portions 44 so as to limit angular movement of the links 13 and 14. The cooperation 55 between the upper projections on the links and the stop plates 46 is clearly shown in Fig. 2.

The operation of the bucket of my invention will now be explained with particular reference to Fig. 2. It will be assumed in the first place 60 that the parts occupy the positions shown in chain lines, the scoops being at their extreme outspread position and the sheave block 26 being at the lower extremity of its path, the bucket being suspended on the holding lines 21 and the closing lines 23 being slack. Under these conditions, the ends of the projections 44 are spaced slightly from the stop plates 46 and the rollers 34 are clear of the guides 36 so that the scoops and the sheave block may move laterally to a 65 limited extent relative to the shroud 10 when the bucket is set down and the holding lines slackened so that the weight is all supported on the lips of the scoops. The extent of this lateral movement, of course, is limited by the engagement 70 of the ends of the projections 44 with the

plates 46 on either side. If the lips are set down on a level surface the direction of this lateral movement is a matter of chance, but if set down on a slope the head will move toward the lower bucket lip, until engagement of stops 5 44 and 46 on the opposite side prevents further movement.

Assuming that the bucket has been deposited with its scoops widespread, upon a pile of material, the closing lines 23 are taken in when it is 10 desired to close the bucket to lift a load of the material. No matter to which side the head structure has moved until restrained by the stops 46, the bringing of the lower block and the upper block closer together will bring the lower 15 block guide sheave 34 and the guide 36 into better alignment, until the alignment is practically perfect when centers of pins 41 and 30 are all in the same plane and the pins 41 at their maximum distance apart. In this position, the stops 44 and 46 almost engage on both 20 sides of the bucket, only sufficient clearance being allowed to prevent binding. The full lines in Fig. 2 show the parts in the position occupied when the pins 30 are a little above the plane 25 defined by pins 41. There is then a slightly greater clearance between the stops on one side or the other.

In the fully open position indicated for the scoops by broken lines in Fig. 2, the axis of the 30 pins 30 is below the axis of the pins 41. As the block is raised, the pins 41 first spread, until they reach their maximum spread, and thereafter come closer together, the final position as shown in Fig. 1 being considerably closer than in the 35 open position. The aligning function of the stop mechanism 44 and 46 is replaced by the aligning function of the rollers 34 and the guides 36 as soon as the roller enters the guides. These 40 guides 36 are flared at the bottom so as to restore the block to central alignment if it be displaced as far as the stops 44 and 46 will permit.

It would be possible to design the mechanism so that the bottom of the guide 36 would bestride the roller 34 when the stops 44 on both 45 sides are nearly in alignment. This, however, would necessitate lengthening the guide, and bringing its bottom nearer to the material to be handled, and for that reason the guide is 50 preferably flared, instead of lengthened.

It will be apparent that the structure of my invention provides centering guides for the closing block which are effective during the upper portion of the path traversed by the block, together with means (the projections 44 and stop plates 46) for maintaining the block approximately centered relative to the frame 10 after the moving block has passed beyond the lower ends of the centering guides. When the scoops are in their extreme widespread position, furthermore, they are free to move off center to a limited extent. Such movement is not great enough to be any serious detriment to the operation of the bucket. In fact, under some circumstances, it is a positive advantage, for example, when the bucket has been lowered onto a sloping pile of material or has been swung from one side to the other as is necessary when unloading material from the hatches of a ship.

The principal advantage of the structure of my invention is the simplicity of the construction, as compared with those known heretofore for effecting similar movements of the scoops. In addition, the centering guides are within the frame or shroud and are, therefore, protected 75

against shocks to which exposed portions are subjected. Since the centering guides terminate at the bottom of the frame, they likewise are protected against possible injury by contact with the material being handled. The structure enables me to get the spread and the desirable closing characteristics common to buckets having link connections instead of corner bars pivoted to one another, without the disadvantages of other guide mechanisms hitherto used. My guide mechanism imposes no unfavorable restrictions upon the "layout." I may make the length of the links 13, and their inclination in the closed position shown in Fig. 1, upon which the final closing power in part depends, whatever is found desirable without introducing undesirable features in the guide mechanism. The scoops thus act effectively in picking up material. There is no depending central portion, furthermore, as in the structures previously known which has to penetrate the material. Instead of keeping the closing block accurately fixed on the centerline throughout its movement, as in the buckets known previously, I simplify the structure by terminating the center guides above the lowermost position of the blocks and provide an additional means to maintain the block approximately in central position.

Although I have illustrated and described a preferred embodiment of the invention, it will be recognized that changes in the construction and arrangement disclosed may be made without departing from the spirit of the invention or the scope of the appended claims.

3.5 I claim:

1. In a clamshell bucket, a frame, links pivoted on opposite sides of said frame near the bottom thereof, a pair of scoops, said links being pivoted to said scoops, respectively, a closing block adapted to be raised from below said frame to within said frame, said scoops having arms

pivoted to said block, a guide member on said block, guide means within said frame for guiding said block guide member as the block is raised within the frame, and cooperating stop means on said frame and links effective to bring said block guide member into alignment with the frame guide when the pivots connecting the scoops to the links are spread as far as the scoop arms will permit.

2. In a clamshell bucket, a frame, links pivoted to opposite sides of said frame near the bottom thereof, a pair of scoops, each link being pivoted to one of said scoops, a closing block, arms extending from each scoop separately pivoted to said closing block, means for co-ordinating the rotation of said scoops about the block pivots, means for raising said block from positions entirely below said frame to positions within said frame thereby closing said scoop, a guide member on said block, straight guide means within said frame, for keeping said block in alignment after entry, said straight guide means terminating above the lowest position of said block, and flaring guide means below said straight guide means for facilitating initial alignment.

3. In a clamshell bucket, a frame, links pivoted to opposite sides of said frame near the bottom thereof, each link being pivoted to one of a pair of scoops, a closing block to which each scoop is separately pivoted, means for co-ordinating the rotation of said scoops about said block pivots, means for raising and lowering said block with respect to said frame, and thereby closing and opening said bucket, guide means on the frame adapted to cooperate with said block and terminating above the lowest position of said block, and stop means for limiting the angular motion of said links with respect to said frame when said block is below the lower limit of said guide means.

40. WILLIAM MAYO VENABLE.
